UNITED STATES PATENT OFFICE

JOHN L. CREVELING, OF NEW YORK, N. Y., ASSIGNOR TO SAFETY CAR HEATING AND LIGHTING COMPANY, A CORPORATION OF NEW JERSEY.

ELECTRIC REGULATION.

1,125,267.

Specification of Letters Patent.

Patented Jan. 19, 1915.

Application filed September 22, 1911. Serial No. 650,697.

To all whom it may concern:

Be it known that I, JOHN L. CREVELING, a resident of New York, in the county and State of New York, have invented certain 5 new and useful Improvements in Electric Regulation, as set forth in the annexed specification and drawing, forming a part thereof.

My invention pertains to that class of 10 electric regulation wherein it is desired to regulate a dynamo or generator in a predetermined manner and has for its particular object to provide means for automatically thus regulating a dynamo.

15 As my invention is particularly applicable to systems of electric distribution wherein a dynamo is used to charge a storage battery and furnish current to lamps or other translating devices, it will be de- 20 scribed in connection with such a system.

The drawing is a diagrammatic representation of one type of system embodying the essentials of my invention.

In the drawing, 1 represents a dynamo 25 or generator provided with the usual field coil 2, having in series therewith the resistance 3, indicated as of the carbon pile variety, and it will be obvious that the dynamo may be regulated by proper manip- 30 ulation of said resistance. This resistance 3 may be controlled by the lever 4 normally drawn in an upward direction, as by adjustable spring 5, in such manner as to tend to compress the carbon pile 3 and 35 lower the resistance thereof. The lever 4 carries at one extremity a core of magnetic material 6 and thus motion imparted to said core may serve to regulate the genera- 40 tor. The resistance 3 may also be con- 45 trolled by the lever 7 normally drawn in a downward direction, as by the adjustable spring 8, in such manner as to tend to compress the carbon pile 3, and lower the resistance thereof. The lever 7 is provided at 50 one extremity with a core 9 of magnetic material and thus the generator may be regulated by motion imparted to the said core. 55 10 represents the positive lead of the generator which is carried to one side of the 50 switch 11, which is preferably of the automatic variety adapted to close the circuit when the voltage of the generator is substantially that of the battery, and as many such switches are known in the art and the

particular type of switch forms no part of 55 my present invention, the presence of one of the well known types is merely indicated diagrammatically. From the switch 11, the lead 10 continues to one side of the switch 12 and is connected with the positive 60 side of the storage battery 13, the negative side of which is connected as by wire 14 with one end of the solenoid coil 15 surrounding the core 6, and having its other terminal connected as by lead 16, to the 65 negative brush of the generator. From the switch 12, the wire 17 is carried to one side of the lamps or other translating devices 18, having their negative terminals connected with the wire 19 which is carried to 70 one side of a translation circuit regulator, in this instance indicated as a carbon pile 20 having its opposite terminal connected as by wire 21, with the solenoid coil 22, the opposite end of which is in connection with 75 the wire 14. The coils 15 and 22 are differentially wound so that if either be alone energized the same will tend to draw the core 6 downwardly against the action of spring 5 and increase the resistance 3, and 80 so wound that current passing through the coil 15 when the battery is being charged will set up a magneto-motive force in the reverse direction to that set up by the coil 22 when the current is passing through coil 85 22 from the lamps or translating devices to the battery. The solenoid coils 15 and 22 are connected in series relation with the generator and translation circuits by the wires 16 and 21 and the coil 15 is connected 90 in series alone with the generator and with the storage battery 13 by the wire 14.

23 is a coil in shunt across the generator circuit surrounding the core 9 in such manner that, when energized, it tends to draw 95 the core 9 upwardly and increase the resistance 3. The carbon pile 20 is controlled by the lever 24 normally drawn in a downward direction as by spring 25 and provided at one extremity with the core 26 surrounded by a solenoid coil 27 in shunt across the translation circuit.

28 represents adjustable stops limiting the motion of levers 4 and 7 which may be used to prevent one lever "following" the other. 105

An operation of the herein shown system comprehending my invention is substantially as follows: If the dynamo be running

at such speed that its electro-motive force be sufficient to charge the storage battery, the switch 11 will be closed and current will flow from the generator through lead 10, 5 switch 11, storage battery 13, wire 14, coil 15 and lead 16 to the generator, and I so adjust the spring 5 that when the desired maximum current is flowing through the battery and coil 15, any appreciable increase above 10 this maximum current will cause the coil 15 to draw the core 6 downwardly against the action of spring 5, and increase the resistance 3, in such manner as to hold this desired maximum charging current from being exceeded. If, now, the battery be charged at 15 this maximum rate until its voltage has risen to the maximum voltage desired to have impressed across its terminals, I so adjust the spring 8 that upon any further increase 20 in voltage across the coil 23, the same will cause the core 9 to be drawn upwardly against the action of spring 8 in such manner as to reduce the pressure upon the carbon pile 3 and increase the resistance thereof 25 so as to prevent this maximum desired voltage being exceeded by the generator in a well-known manner. If, now, the lamp circuit be closed, as by closing the switch 12, current will flow through switch 12, wire 17, 30 translating devices 18, wire 19, resistance 20, wire 21 and solenoid coil 22, thence through solenoid 15 and wire 16 to the generator, and as the solenoid coil 22 is wound in such direction that this coil when thus traversed 35 by current opposes the action of the charging current in the coil 15, the effect of the lamp load will be to cause a greater current to be necessary in the coil 15 in order to draw the core 6 downwardly against the 40 spring 5 and thus the generator output will be increased in proportion to the lamp or translation circuit load flowing through the coil 22. If the voltage across the translating devices be in excess of that desired to have 45 impressed upon the same, I so adjust the spring 25 that the coil solenoid 27 will raise the core 26 and lever 24 and increase the resistance 20 until the proper voltage is impressed upon the translation circuit, then 50 any tendency to rise above this voltage will cause the resistance 20 to be increased and any fall in voltage will cause the resistance 20 to be decreased in such manner as to hold the voltage upon the translation circuit substantially constant.

From the foregoing, it will be plain that I have produced a system wherein the generator is automatically controlled to charge a storage battery upon a constant potential 60 circuit, upon certain conditions of the battery and upon a constant current circuit upon other conditions of the battery. Also, that the output of the generator is automatically increased as current is supplied to the 65 translation circuit and the said current regu-

lation of the generator is affected by the operation of the translation circuit regulator by control of the current in the coil 22.

I do not wish in any way to limit myself to the exact system set forth in this application merely to illustrate one type of system comprehending the essentials of my invention, for it will be obvious that wide departure may be made without departing from the spirit and scope of my invention which is as set forth in the following claims:

I claim—

1. The combination with a generator, a main circuit, a storage battery, a translation circuit, and means for regulating the generator embracing a single variable resistance and, control means therefor including two differentially wound coils located in series with the generator and the translation circuit, one of said coils being connected in series with the battery, and additional control means acting upon the same variable resistance including a coil connected to be actuated by the generator only.

2. The combination with a generator, a main circuit, a storage battery, a translation circuit, and means for regulating the generator embracing a single variable resistance and control means therefor adapted to be acted upon by two differentially wound coils located in series relation with the generator and the translation circuit, one of said coils being additionally connected in series with the battery, and additional control means acting upon the same variable resistance and including a coil connected to be actuated by the generator only.

3. The combination with a generator, a main circuit, a storage battery, a translation circuit, and means for regulating the generator embracing a single variable resistance, spring controlled means therefor adapted to be operated upon by a solenoid embracing two differentially wound coils located in series with the generator and the translation circuit, one of said coils being additionally connected in series with the battery and a second spring controlled means acting upon the same variable resistance and embracing a solenoid coil connected to be actuated by the generator, and a core actuated by the last-named coil to oppose the last-named spring controlled means.

4. The combination with a generator, a main circuit, a storage battery, a translation circuit, and means for regulating the generator embracing a single variable resistance and resistance varying means operating upon the opposite ends of said resistance; together with control means therefor, one of said control means constituting two differential coils located in series relation with the generator and the translation circuit, one of said coils being connected also in series with the battery, the other control means embrac-

ing a solenoid coil connected to be actuated by the generator, and spring controlled means for opposing the operation of said coils.

5. The combination with a generator, a main circuit, a storage battery, a translation circuit, and means for regulating the generator embracing a single variable resistance and resistance varying means operating 10 upon the opposite ends of said resistance; together with control means therefor, one of said control means constituting differentially wound coils located in series relation between the generator and the translation 15 circuit, one of said coils being connected also in series with the battery, and additional control means acting upon the same variable resistance and embracing a coil connected to be actuated by the generator only.
- 20 6. The combination with a generator, a main circuit, a storage battery, a translation circuit, and means for regulating the generator embracing means for providing resistance, and control means, including two differentially wound coils located in series with 25 the generator and the translation circuit, one of said coils being connected in series with the battery, and additional control means including a coil connected to be actuated by 30 the generator only.

7. The combination with a generator, a main circuit, a storage battery, a translation circuit, and means for regulating the generator embracing means for providing resistance, and control means adapted to be acted 35 upon by two differentially wound coils located in series relation with the generator and translation circuit, one of said coils being additionally connected in series with the 40 battery, and additional control means including a coil connected to be actuated by the generator only.

8. The combination with a generator, a main circuit, a storage battery, a translation

circuit, and means for regulating the generator embracing means for providing resistance, spring-controlled means adapted to be operated upon by a solenoid embracing two differentially wound coils located in series with the generator and the translation circuit, one of said coils being additionally connected in series with the battery, and a second spring-controlled means embracing a solenoid coil connected to be actuated by the generator, and a core actuated by the last-named coil to oppose the last-named spring-controlled means.

9. The combination with a generator, a main circuit, a storage battery, a translation circuit, and means for regulating the generator embracing means for providing resistance and resistance varying means, together with control means therefor, constituting two differential coils located in series relation with the generator and the translation circuit, one of said coils being also connected in series with the battery, and other control means embracing a solenoid coil connected to be actuated by the generator, and spring-controlled means for opposing the operation 70 of said coils.

10. The combination with a generator, a main circuit, a storage battery, a translation circuit, and means for regulating the generator embracing means for providing resistance and resistance varying means, together with control means for the resistance varying means, constituting differentially wound coils located in series relation with the generator and the translation circuit, one of 80 said coils being connected also in series with the battery, and additional control means embracing a coil connected to be actuated by the generator only.
